UNITED STATES PATENT OFFICE.

FRANK W. BROWN, OF WILKINSBURG, AND ARCHIE R. MARSHALL, OF PITTSBURGH, PENNSYLVANIA, ASSIGNORS TO CENTRAL RAILWAY SIGNAL COMPANY, OF PITTSBURGH, PENNSYLVANIA, A CORPORATION OF NEW JERSEY.

RAILWAY SIGNAL TORPEDO.

Application filed March 4, 1922. Serial No. 541,180.

To all whom it may concern:

Be it known that we, FRANK W. BROWN, of Wilkinsburg, in the county of Allegheny and State of Pennsylvania, and ARCHIE R. MARSHALL, of Pittsburgh, in the county of Allegheny and State of Pennsylvania, citizens of the United States, have invented new and useful Improvements in Railway Signal Torpedoes, of which the following 5 is a specification, reference being had herein to the accompanying drawings.

This invention relates to improvements in railway signal torpedoes, provided with a rail-engaging member for fastening the 10 torpedo to the rail-head of a track.

The object of our invention is to provide a means for attaching a rail-engaging member to a fibre or paper torpedo case in such a manner that the pulling open or separation of the ends of the clasp to attach it to the rail will not tend to separate the folded portions of the case.

A further object of our invention is to provide the rail-engaging primary attaching means with clamping ears for firmly clamping the outer folds of the case in their folded positions so that they cannot become displaced either in shipment or in handling.

A further object of our invention is to form a fibre or paper torpedo case from a sheet or blank and so fold it around the explosive compound that the same is wholly enclosed, and providing means whereby a lead or spring-rail-attaching member may be securely fastened thereto, and at the same time providing a torpedo with a thick bottom and flat lower face whereby it will more fully rest upon the rail.

A still further object of our invention is to provide a clip for the torpedo case having a novel construction and arrangement of parts which will be hereinafter more fully set forth.

Another object of our invention is to provide a torpedo which is cheap in construction, simple of manufacture and efficient in use.

Other further objects and improved results of our new torpedo will appear in the following specification and accompanying drawings.

In the drawings:

Figure 1 is a perspective view of a torpedo embodying our invention.

Fig. 2 is a bottom view of our improved 55 torpedo.

Fig. 3 is a vertical sectional view taken transversely of the rail-engaging member.

Fig. 4 is a vertical sectional view taken longitudinally of the rail-attaching member. 60

Fig. 5 is a plan view of the explosive wrapper or case, the case being shown in extended form.

Fig. 6 is a top plan view of the torpedo clip. 65

Fig. 7 is a bottom view of a modified form of our invention.

Fig. 8 is a vertical sectional view taken on the line 8—8 of Fig. 7, looking in the direction indicated by arrows. 70

Fig. 9 is a bottom plan view of a torpedo constructed similarly to that shown in Fig. 8, with the exception that a spring rail-engaging member is shown.

Fig. 10 is a vertical sectional view taken 75 on the line 10—10 of Fig. 9, looking in the direction indicated by arrows.

Fig. 11 is a bottom plan view of a torpedo, showing the incorporation of another modification of our invention. 80

Fig. 12 is a vertical sectional view of a torpedo showing another form of our invention, the section being taken longitudinally of the rail-engaging member.

Fig. 13, is a bottom view of the torpedo 85 shown in Fig. 12.

Fig. 14 is a bottom plan view of a torpedo showing another form of our improved invention.

Fig. 15 is a vertical sectional view of the 90 torpedo, shown in Fig. 14, the section being taken longitudinally of the rail-attaching member.

In the drawings like parts are designated by similar reference numerals throughout 95 the description.

Referring now to Figs. 1 to 6, inclusive, 1 designates a torpedo explosive which is made preferably in a tablet form, although, if so desired, loose powder can be used. 100

The explosive case or wrapper is designated by A and the explosive 1 is carried within the depression 2, of the central portion 3 of the case. The case is provided with outwardly extending end portions 4 and 5 and outwardly extending side portions or flaps 6 and 7. The length of end portion or flap 4 is less than the length of the cen-

tral portion 3; and 5 is of a length greater than the length of the central portion 3 of the case A, so that the flaps completely cover the explosive 1 when they are folded inwardly upon the same.

The end portion or flap 5 of the case A is provided with openings or slits 8, arranged in separated relation to each other.

We have further provided a clip 9, preferably constructed of sheet tin, although some other suitable material could be used, which is of a size equal to the central portion 3 of the explosive case A. The clip 9 is provided at its ends with outwardly extending ears 10 and its central portion is provided with openings or slits 11 positioned in separated parallel relation. The clip 9 is further provided with ears 12, preferably cut from the clip itself, and positioned one at each side 20 of the portion 13 of the clip which separates the openings 11 therein.

We have shown a spring rail-engaging member 14 provided with an approximately flat top 15 having therein U-shaped bends 25 or crimps 16 in separated relation.

In assembling our torpedo the portions 3, 4, 6 and 7 of the case are coated with cement and the explosive 1 is then placed in the depression 2 of the case. The end portion or 30 flap 4 is then folded inwardly upon the explosive 1 and its outer face coated with cement. The clip 9 is then placed upon the under surface of the end flap 5, as illustrated in Fig. 5, in such a manner that the openings 8 and 11 of the members register. The rail-engaging member 14 is then threaded 35 through the registering openings of the clip and the end flap of the case in such a manner that the top 15 of the rail-engaging member lies against the inner face of the end-flap 5, the ends 17 of the rail-engaging member extending downwardly and outwardly from the openings. The U-bends 16, in the top of the rail-engaging member 40 likewise extend downwardly through the openings of the clip and end-flap and hold the rail-engaging member against endwise movement in its retainer. The openings 8 and 11 are of a length approximately equal 45 to the width of the rail-engaging member so as to snugly receive the same and guard against transverse movement of the rail-engaging member.

With the rail-engaging member threaded 50 through the end-flap 5 and the clip 9, these members are then folded inwardly upon the previously inwardly folded end-flap 4 of the case. To complete the torpedo, the previously cement coated side-flaps 6 and 7 are 55 folded inwardly upon the clip 9. As clearly appears in the drawings, these portions are formed so as to extend inwardly only so far as the ears 12 of the clip 9, and these ears 12 are clamped downwardly upon the 60 flaps to positively lock them in place. To

further lock the outer folds 6 and 7 in place upon the clip 9, the ears 10 of the clip are clamped inwardly upon the ends of the folds.

From the foregoing it will be seen that we have furnished a completed torpedo, but if it is desired the torpedo can be subjected to a waterproofing bath so as to insure against dampness penetrating its explosive case and reaching the explosive compound.

It will be further seen that we have provided a torpedo in which the outer folds of the case do not extend over the rail-engaging member and thereby have prevented any likelihood of the case holding the rail-engaging member in a spread or extended position. If it be so desired, a lead strip can be substituted in place of the spring rail-engaging member.

We desire further to point out that with the outer folds of the case being doubly locked in position by the inwardly clamped ears 10 at their ends and the inwardly clamped ears 12 at their center, we have provided a torpedo which will withstand handling both in shipping and in use without the likelihood of the outer folds of the case becoming displaced and thereby endangering the complete destruction of the torpedo which would occur should the outer 95 folds become loose. Should the outer folds of the case become loose not only would the explosive be likely to become damp, but the entire case would in all probability become unfolded and thereby render the torpedo 100 worthless.

Referring now to our modified construction, as shown in Figs. 7 and 8 of the drawings, in this torpedo the explosive 17, which is preferably of tablet form, is carried within an open ended wrapper 18, which has outwardly extending end-portions 19 beyond the ends of the explosive. A metal clip 21, similar in construction to the previously described metal clip 9, is placed upon the bottom of the torpedo-wrapper 18 and the outwardly extending end-portions 19 are folded down upon this clip 21 as at 20. The clip 21 carries at its ends outwardly extending ears 22, which are bent inwardly upon the end portions 20 of the torpedo-wrapper to hold them in place. The clip 21 is further provided with ears 23, preferably cut from the clip 21, and positioned one at each side of the center portion 24 of the clip. These ears 23 are bent downwardly upon the end portions 20 of the torpedo-wrapper to further hold them in folded position.

The center portion 24 of the clip is formed between slits 25, which are positioned in separated parallel relation, as clearly appears in Fig. 7 of the drawing.

In this figure of the drawing, we have shown the rail-engaging member 26 in the form of a lead strap, which is threaded 130

through the opening 25 in the metal clip 21. In fastening the torpedo to a rail-head, the metal rail-strap 26 is bent around the rail-head and holds the torpedo in place upon the rail.

In Figs. 9 and 10 of the drawings, the construction is identical with that described in Figs. 7 and 8, with the exception that we have shown a spring-clip 27 as the form of rail-engaging member which may be employed. As the construction of the torpedo in these two figures is the same as in Figs. 7 and 8, numerals have been applied to these figures identical with those applied to Figs. 7 and 8, and no further description is, therefore, given.

In the form of torpedo shown in Fig. 11, we have used the torpedo-wrapper 18, previously described, having the inwardly bent end-portions or flaps 20. In the construction shown in this figure, a metal clip 28 is used which is provided with inwardly and downwardly bent corner projecting ears 29 and downwardly bent centrally located earportion 30 to hold the inwardly bent end-portions 20 of the torpedo-wrapper in place.

We have here shown a lead strap 31, as the form of rail-engaging member. As clearly appears in this figure, the strap 31 passes beneath the metal clip 28 and is retained in place by the punching or depressing the metal clip 28 at a plurality of points, as at 32, downwardly into engagement with the strap.

Referring now to Fig. 12 of the drawings, we have here employed a form of torpedo-wrapper, as shown in Figs. 1 to 6, inclusive, of the drawings. The explosive is designated at 33, being preferably of tablet form, carried within the several folds of the case 34. This case has extending flap portions 35, 36, 37 and 38. A metal clip 39 is carried beneath the inwardly bent portions 37 and 38 of the case and retains these portions in their folded position by the medium of inwardly and downwardly bent corner ears 40. The metal clip 39 is further provided with centrally located ears 41, which are depressed upon the inwardly bent portions 37 and 38 of the torpedo wrapper to hold them in folded position.

The clip 39 is provided with centrally located openings or slits 42, positioned in separated parallel relation. Through the openings 42 is threaded the rail-engaging member 43, which is shown in the form of a spring clip similar to that shown in Figs. 1 to 6, inclusive, of the drawings. The central portion 44 of the rail-engaging member lies beneath the central portion 45 of the metal clip 39, while U-bends 46 in the rail-engaging member 43 extend downwardly through the openings 42 of the clip and hold the rail-engaging member against endwise movement in the clip.

The form of torpedo construction, shown in Figs. 12 and 13 of the drawings is similar to that shown in Figs. 1 to 6, inclusive, of the drawings, with the exception that the rail-engaging member is not threaded through one of the inwardly folded end flaps of the torpedo case.

In Figs. 14 and 15 of the drawings, we have shown a construction identical to the construction shown and described in Figs. 12 and 13 of the drawings, with the exception of the rail-engaging member.

In these two figures of the drawings, the rail-engaging member is designated by 47 and is a lead strap threaded through the openings 42 in the clip 39, in such a manner that the strap crosses above instead of below the central portion 45 of the clip, which lies between the clip-openings 42. Due to this manner of threading the strap it extends outwardly from beneath the metal clip 39, whereas, in the other forms of torpedo constructions, shown and described herein, the rail-engaging members have been passed under the central portions of the clips and extended outwardly from the sides of the torpedo above the metal clip, which holds them to the torpedo.

As this form of torpedo is similar to the form shown in Figs. 12 and 13, with the exception of the rail-engaging member, similar reference numerals have been given to Figures 14 and 15 of the drawings as those applied to Figures 12 and 13.

It will be readily understood that when desired that all the forms of the torpedoes herein shown and described can be subjected to a water-proofing bath so as to insure against dampness penetrating the explosive case and reaching the explosive compound.

The features of advantages described in relation to the constructions shown in Figs. 1 to 6, inclusive, of the drawings, are also applicable to the other forms of torpedoes shown and described herein.

Having thus described our invention, what we claim and desire to secure by Letters Patent is:

1. An improved railway signal torpedo, comprising a case having inwardly folded extending portions, an explosive within the case, a clip carried by the torpedo below the inwardly folded portions thereof, the clip having openings for the passage of a rail-engaging member, and the inwardly folded extended portions folded inwardly upon the clip and held in their folded positions thereby.

2. An improved railway signal torpedo, comprising a case, having inwardly folded extending portions, a clip carried by the torpedo below said folded portions, the clip being provided with openings for the passage of a rail-engaging member, the clip being further provided with ears at its end

- corners and adjacent its openings, and the inwardly folded portions of the case being retained in their folded position by the clip ears. 45
5. An improved railway signal torpedo, comprising a case made up of overlapping flaps and outer folds, an explosive within the case, a clip carried by one of said flaps, the clip and its carrying flap having openings for the passage of a rail-engaging member, the clip provided with ears at its end-corners and ears within the margin of the clip and adjacent its openings, and the outer folds of the case folded inwardly and 50 retained in their folded position by the clip ears. 55
6. An improved railway signal torpedo, comprising a case made up of a plurality of folds of material, a clip carried by one of said folds, an explosive carried within the case, the clip provided with ears, and the outer folds of the case folded inwardly upon opposite edges of the clip and retained in their folded positions by the clip ears. 60
7. An improved railway signal torpedo, comprising a case made up of a plurality of folds of material, a clip carried by one of said folds, openings in the clip and its carrying fold for receiving a rail-engaging member, a clip provided with ears at its opposite end corners and at opposite sides of the clip openings, and the outer folds of the case folded inwardly upon the clip in parallel relation to the rail-engaging member and retained in their folded position by the clip-ears. 65
8. An improved railway signal torpedo, comprising a case made up of overlapping flaps, an explosive within the case, a clip carried by one of said flaps, the clip and flap having openings for the passage of a rail-engaging member, a rail-engaging member having approximately U-shaped bends in its 70 top, and the U-shaped bends of the rail-engaging member extending outwardly through the openings in the clip and flap, for the purpose described. 75
9. An improved railway signal torpedo, comprising a case made up of overlapping flaps, an explosive within the case, a clip carried by one of said flaps, the clip and flap having openings for the passage of the rail-engaging member, a rail-engaging member having approximately U-shaped bends in its top, the outer folds of the case folded inwardly upon the clip and held in their folded positions thereby, and the U-shaped bends for the rail-engaging member extending outwardly through the openings in the flap and clip, for the purpose described. 80
10. An improved railway signal torpedo, comprising a case having inwardly folded extending portions, a clip carried by the torpedo beneath said folded portions, a rail engaging member for the torpedo, the clip being provided with ears at its end corners and ears within its margins, and the inwardly folded portions of the case being retained in their folded position by the clip ears. 85

In testimony whereof, we hereunto affix our signatures.

FRANK W. BROWN.
ARCHIE R. MARSHALL.
